REFRIGERATOR DOOR

Montgomery Ferar, Detroit, Mich., assignor to
Seeger Refrigerator Company, St. Paul, Minn.,
a corporation of Minnesota

Application July 14, 1950, Serial No. 11,167

Term of patent 3½ years

(Cl. D67—3)

To all whom it may concern:

Be it known that I, Montgomery Ferar, a citizen of the United States and a resident of Detroit, in the county of Wayne and State of Michigan, have invented a new, original, and ornamental Design for a Refrigerator Door, of which the following is a specification, reference being had to the accompanying drawing, forming a part thereof.

Fig. 1 is a front elevational view of a refrigerator door, embodying my new design;

Fig. 2 is a top plan view of the same door; and
Fig. 3 is a side elevational view thereof.

The dominant features of my design reside in the portions shown in full lines.

I claim:

The ornamental design for a refrigerator door, as shown and described.

MONTGOMERY FERAR.
